(57) **CLAIM**

The ornamental design of a collapsible portable container, as shown and described.

DESCRIPTION

FIG. 1 is a front and left side perspective view of the collapsible portable container fully opened (unfolded); FIG. 2 is a further front and left side perspective view of the collapsible portable container fully opened, with a separate stiff panel not part of the design shown in dotted line; FIG. 3 is a front elevation view of the collapsible portable container fully opened; FIG. 4 is a rear elevation view of the collapsible portable container fully opened; FIG. 5 is a left side elevation view of the collapsible portable container fully opened; FIG. 6 is a right side elevation view of the collapsible portable container fully opened; FIG. 7 is a top plan view of the collapsible portable container fully opened; FIG. 8 is a bottom plan view of the collapsible portable container fully opened; FIG. 9 is a front and left side perspective view of the collapsible portable container partially folded; FIG. 10 is a front and left side perspective view of the collapsible portable container further partially folded; FIG. 11 is a front and left side perspective view of the collapsible portable container fully folded; FIG. 12 is a front elevation view of the collapsible portable container fully folded; FIG. 13 is a rear elevation view of the collapsible portable container fully folded; FIG. 14 is a left side elevation view of the collapsible portable container fully folded; FIG. 15 is a right side elevation view of the collapsible portable container fully folded; FIG. 16 is a top plan view of the collapsible portable container fully folded; FIG. 17 is a bottom plan view of the collapsible portable container fully folded;

(Continued)

FIG. 18 is a front and left side perspective view of the collapsible portable container fully opened, with a portion of an associated supporting golf cart not part of the design shown in dotted line; and,

FIG. 19 is a front and left side perspective view of the collapsible portable container fully folded, with a portion of an associated supporting golf cart not part of the design shown in dotted line.

The broken line showings of the separate stiff panel and the associated supporting golf cart are included for the purpose of illustrating environmental structure and form no part of the claimed design.
